DESIGN FOR A COMBINED WASHING MACHINE AND WRINGER

Julian L. Perkins, West Springfield, Mass.

Application June 1, 1934, Serial No. 52,011

Term of patent 3½ years

To all whom it may concern:

Be it known that I, JULIAN L. PERKINS, a citizen of the United States, residing at West Springfield, in the county of Hampden and State of Massachusetts, have invented a new, original, and ornamental Design for a Combined Washing Machine and Wringing, of which the following is a specification, reference being had to the accompanying drawing, forming part thereof:

Fig. 1 is a side elevational view of the combined washing machine and wringer showing my new design, and

Fig. 2 is a sectional plan view on the line 2—2 of Fig. 1.

I claim:

The ornamental design for a combined washing machine and wringer substantially as shown.

JULIAN L. PERKINS.
